CARL F. BRANDENBERGER AND MARTIN W. REUTHER, OF FORT MADISON, IOWA.

SUCTION-PUMP.

1,194,705.

Specification of Letters Patent. Patented Aug. 15, 1916.

Application filed January 4, 1916. Serial No. 70,210.

To all whom it may concern:

Be it known that we, CARL F. BRANDENBERGER and MARTIN W. REUTHER, citizens of the United States, residing at Fort Madison, in the county of Lee, State of Iowa, have invented a new and useful Suction-Pump, of which the following is a specification.

The present invention appertains to pumps, and aims to provide an air chamber and drain storage for suction pumps, said device allowing the head of the water to drain down through the piston or plunger into the chamber to be stored therein, sufficiently below the surface of the soil to avoid the freezing of the water, the water flowing into the pump barrel or cylinder as soon as the piston is operated, to prime the pump quickly and effectively.

The present invention embodies an air chamber in communication with the barrel of the pump above the lower check valve, there being a check valve between said air chamber and the piston, the valve of the piston and the second mentioned check valve each being apertured so that the head of water supported above the lower check valve can drain downwardly through the piston and second mentioned check valve into the air chamber, in order that the water level can lower sufficiently below the surface of the soil to prevent freezing. The present device does not impair the utility of the pump, but to the contrary enhances the efficiency thereof, and eliminates the freezing of the water.

It is also within the scope of the invention to provide an appliance of the nature indicated which is comparatively simple and inexpensive in construction, which can be readily installed upon various pumps, and which will serve its office in a thoroughly practical, reliable, and efficient manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a fragmental vertical section

of a pump illustrating one form of the invention, portions being shown in elevation. Fig. 2 is an enlarged sectional view of the check valve forming a part of the invention. Fig. 3 is a view similar to Fig. 1 of a modified form adapted especially for use in wells of small diameter. Fig. 4 is an enlarged cross section on the line 4-4 of Fig. 3. Fig. 5 is a view similar to Figs. 1 and 3 of another variation.

Referring specifically to Figs. 1 and 2, the pump illustrated therein embodies a vertical barrel or cylinder 1 having attached to its upper end a reducer 2 connected to the lower end of the upper pipe section 3 of the pump. A reducer 4 is engaged to the lower end of the barrel 1 and is connected to the upper end of the lower pipe section 5, so that the barrel is interposed in the ordinary manner in the suction pipe. The reducer 4 is provided with a valve seat 6 for the lower check or clack valve 7 having the annular surrounding portion 8 clamped between the reducer 4 and lower end of the barrel 1 in the ordinary manner. The piston or plunger 9 works within the barrel 1 as usual, and has an arched spider 10 connected to the lower end of the plunger rod 11 which projects upwardly through the pipe section 3 to be reciprocated in the ordinary manner. The piston 9 has the usual opening 12 and surrounding valve seat upon which is seated a check valve 13 within the spider 10.

The foregoing parts are common in suction pumps, the barrel 1 being located several feet below the surface of the soil within the well, or below the frost line.

In carrying out the invention, a laterally or horizontally projecting pipe 14 has one end attached to one side of the barrel 1 adjacent the lower end thereof and immediately above the lower check valve 7, and the other end of said pipe 14 is upturned and connected to the lower end of an air chamber 15. A check valve is interposed in the pipe 14, the same embodying a casing 16 interposed in said pipe, and having a partition 17 therein provided with a by-pass aperture 17a and an opening 18 forming a beveled seat for the check valve 20 which is of frusto-conical form to seat downwardly in said opening 18. The check valve 20 is seatable toward the chamber 15, so as to be seated when the water flows into the chamber 15, and to be unseated when

the water is drawn out of said chamber. The valve 20 has a depending guide stem 21 to hold the valve in place, and said valve also has an upstanding stem 22 working within 5 the recess 23 with which the cap 19 of the casing 16 is provided. The valve 20 is provided with a restricted aperture 24 therein allowing for the restricted flow of water therethrough even though the valve 20 is seated. The check valve 13 of the piston 9 is also provided with a restricted aperture 25, which does not materially affect the operation of the pump, but which allows the water above the piston to drain downwardly 10 through the said valve 13 when the pump is idle. The barrel 1 has an outstanding boss 26 to which the pipe 14 is connected and said boss is located below the piston 9.

When the pump is in operation, the reciprocalation of the piston 9 elevates the water in the ordinary manner, the check valve 7 supporting the head of the water, and the piston 9 lifting the column of water intermittently. The suction created extends 20 into the chamber 15 to draw the water therefrom and to rarefy the air therein, the valve 20 unseating when the piston 9 is raised, and seating when the piston is lowered. This tends to create a vacuum within the 25 chamber 15 during the operation of the pump. As soon as the operation of the piston 9 is stopped, the suction in being relieved within the chamber 15 will allow the air therein to resume normal conditions, 30 and this will draw the water from the barrel 1 into the chamber 15, said water flowing through apertures 24 and 17^a past valve 20. The head of water above the piston 9 can drain downwardly through the aperture 25 35 to flow past the piston and thence to and through the pipe 14 into the chamber 15. It will thus be seen that when the pump is idle, the head of water will drain downwardly through the piston so as to be drawn 40 into the chamber 15, and since said chamber is below the frost line, the water therein will not freeze, and this will prevent the 45 freezing of the pump since the water level therein will be lowered sufficiently to avoid this. When the pump is again started, the upward movement of the piston 9 will create a suction within the lower portion of the barrel 1, thereby drawing the water quickly from the chamber 15, to prime the 50 pump, the valve 20 unseating to allow the water to flow quickly from the chamber 15 into the barrel 1.

The form of the invention illustrated in Fig. 1 can be used in wells of larger diameter, and when the device is to be used in a drilled or small-diametered well, the form illustrated in Figs. 3 and 4 is preferably employed. The parts designated 1 and 13, inclusive, in Figs. 3 and 4 are the same as 55 the similarly numbered parts in Fig. 1, so

that the description need not be reiterated. In the modified form, however, the reducer 4 instead of being attached to the lower end of the barrel is attached to the lower end of a chamber 15', and a reducer 16' is 70 threaded onto the lower end of the barrel 1 and has an annular valve seat 18' therein upon which is seatable a check or clack valve 20' similar to the valve 7, and having a surrounding annular portion 17' clamped between the reducer or valve casing 16' and the lower end of the barrel 1. A vertical pipe 14' has its upper end engaged with the reducer 16' and is threaded or otherwise engaged downwardly through the upper end 80 of the chamber 15' to project downwardly therein to a point adjacent the lower end or bottom of the chamber 15'. The aperture of the boss 26 is closed by a plug 27, and the pipe 14' is provided with an aperture 85 28 adjacent the upper end or top of the chamber 15'. A lock nut 50 is threaded on the pipe 14' to seat on the chamber 15' to prevent leakage. In the modified form, the valve 20' resembles the valve 20 above described, the pipe 14' resembles the pipe 14, and the chamber 15' resembles the chamber 15. During the operation of the piston 9, the water is sucked upwardly past the lower check valve 7 through the chamber 15' and 95 pipe 14' past the valve 20' into the barrel 1 to be raised by the piston, it being noted that the suction created by the piston will rarefy the air within the chamber 15' above the lower end of the pipe 14'. Therefore, 100 as soon as the pump is stopped, the head of water can drain downwardly through the piston and aperture 24' of the valve 20' to flow downwardly through the pipe 14' into the chamber 15', so that the water will be 105 stored within said chamber below the frost line. The aperture 28 permits of the flow of air from and into the upper portion of the chamber 15'. As soon as the pump is started, the suction will draw the water 110 from the chamber 15'.

The variation illustrated in Fig. 5 is a combination of the two forms illustrated in Figs. 1 and 3, as will be obvious by referring to said figures and comparing the reference characters. A vertical coupling 29 connects the reducers 4 and 16' and has a lateral boss 30 to which is connected the pipe 14'' attached to the lower end of the upright air chamber 15. The operation of 115 the structure illustrated in Fig. 5, will be readily understood from the foregoing, since it is practically the same. In this form, the reducer 16' and coupling 29 are integrated.

In each form of the invention, there is provided an air chamber having its lower portion in communication with the lower portion of the pump barrel or cylinder below the piston and above the lower check 130

valve, the piston being provided with a restricted aperture to allow the water thereabove to drain downwardly, and a check valve being disposed between the chamber and pump barrel to seat toward said chamber and having a restricted aperture to allow the water to flow from said barrel into said chamber. These are salient features of the invention, although it is evident that the several forms have details which are of advantage.

Having thus described the invention, what is claimed as new is:

The combination with a pump embodying an upright barrel, a piston working therein and having a check valve provided with a restricted drain aperture, and a lower check

valve for supporting the head of water, of an air chamber having its lower portion in communication with the lower portion of said barrel below the piston and above said check valve, and a check valve between said barrel and chamber and seating toward said chamber, the last mentioned valve having a restricted aperture.

In testimony that we claim the foregoing as our own, we have hereto affixed our signatures in the presence of two witnesses.

CARL F. BRANDENBERGER.
MARTIN W. REUTHER.
